UNITED STATES PATENT OFFICE.

JOSEPH H. TILLINGHAST, OF STOCKTON, CALIFORNIA, ASSIGNOR TO ARTHUR P. TATTERSON AND GEORGE W. TATTERSON, OF STOCKTON, CALIFORNIA.

WOOL-WASHING MACHINE.

SPECIFICATION forming part of Letters Patent No. 784,240, dated March 7, 1905.

Application filed April 29, 1904. Serial No. 205,578.

To all whom it may concern:

Be it known that I, JOSEPH H. TILLINGHAST, a citizen of the United States, residing at Stockton, in the county of San Joaquin and State of California, have invented certain new and useful Improvements in Wool-Washing Machines; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to certain improvements in that class of forking, elevating, and conveying machines used for handling fibrous and analogous materials during the cleansing process, more particularly wool.

20 My object is to introduce a more cheaply-constructed machine which will thoroughly agitate the wool while in the washing tub or vat, convey the same to the end of said tub or vat, and then elevate said wool to a conveyer, 25 which deposits it into the squeeze or wringer rolls regularly by mechanical means automatically, my principal object being to reduce the wearing parts to a minimum, so as to require less power to operate and prolong the life of 30 the machine. This I accomplish by the peculiar construction, novel combination, and adaptation of parts hereinafter described, and particularly pointed out in the claims hereunto annexed, reference being had to the accompanying drawings for a better understanding thereof, in which—

Figure 1 is a side elevation of my improved machine. Fig. 2 is a front elevation of the same, showing the swing-frame, power-shaft, 40 fork, and posts. Fig. 3 is a detached side elevation of the fork-operating mechanism viewed from the fork 10", and Fig. 4 is an elevation of the same viewed from the opposite side or outside of the tub or vat. Fig. 5 is a plan view of my machine, showing more particularly the construction of the rake and its supporting mechanism.

Similar figures of reference indicate corresponding parts throughout all the views.

1 represents the squeeze or wringer rolls, 50 which are of the form and function of those in general use and are located in suitable bearings at one end of a suitable tub or vat 2, such as is used for washing wool or other analogous fibrous material. An apron or conveyer 55 formed, preferably, of series of rollers 3 is located in juxtaposition to the squeeze-rolls 1 over the tub or vat 2, as shown in Fig. 1.

I arrange and attach posts 4 one on either side of and at a suitable point longitudinally 60 on the vat or tub 2 and directly opposite to each other. A power-shaft 5 is journaled on the said posts 4 near the top of the same in suitable bearings. Said power-shaft 5 is operated by a power-pulley 6, rigidly attached 65 thereto. A swing-frame is suspended from and pivoted to the shaft 5 and is composed of the oscillating arms 7, which have their upper ends journaled on the shaft 5 and the cross-bar 8, adapted to stiffen the said arms 7. The 70 arms 7 at their lower ends are adapted to carry a fork-shaft 9, which is journaled theron. Said fork-shaft 9 is provided with a fork 10, rigidly secured at a suitable point thereon. The fork 10 is operated intermittently by 75 means of sprocket wheels and chains extending between said shaft 5 and said shaft 9. I use preferably three of the arms 7, two of which are arranged close together, as shown in Fig. 2, between which the shaft 5 is adapted 80 to carry a sprocket 11, rigidly secured thereto. A sprocket-chain 12 engages the wheel 11 and communicates motion to a similar sprocket-wheel 13, which is loosely mounted or journaled on the shaft 9 between the arms or 85 members 7. The sprocket-wheel 11 is adapted to make six revolutions to two revolutions of the sprocket-wheel 13, while the said shaft 9 is making one complete movement forward and back, as more fully hereinafter described. A 90 cog-wheel 14 is also journaled on the shaft 9 and attached to and adapted to revolve with the said sprocket-wheel 13. A similar cog-wheel 15, adapted to engage said wheel 14 through the

medium of an idler 16 has a shaft 17 and is suitably journaled in brackets 18 on the oscillating arms 7, as shown in Figs. 1 and 2. The inner end of said shaft 17 is adapted to carry a double cam 19, which is adjustable by means of a slot 20 and cap-screw secured in the end of the shaft 17. The cam 19 is provided with two pins 21 and 22, one longer than the other, for the purposes as will be shown herein. The said wheel 15 is adapted to make one revolution to two revolutions of the wheel 14. The shaft 9 between the oscillating arms 7 is adapted to carry a fork-operating ratchet-wheel 23, which is rigidly attached to the same. The wheel 23 has a slot in its periphery in which is fitted a removable lug 24, which is rigidly secured to the side of said wheel 23, and has a slot 25, (shown more particularly in Fig. 3,) which is adapted to be engaged intermittently by a pawl 26, which is carried by the sprocket-wheel 13, which has a lug 27 in its side for that purpose. The pawl 26 is pressed into engagement with the slot 25 by a spring 28, which has one end rigidly attached to the side of the wheel 13, the other end engaging with said pawl 26. Said pawl 26 has a lug on one end which is adapted to engage with the pin 21 at each alternate revolution of the wheel 13, said pin 21 and cam 19 being adjusted so to do. The lug 24 protrudes from the side of the wheel 23 and is adapted to be engaged by a pawl 29, which is pivoted to one of the arms 7, as shown in Fig. 2. The lug 24 has an auxiliary notch 30 to the rearward 35 of the slot 25 for the purpose as will be shown.

A rake-frame composed of the longitudinal bars 31 and the cross-pieces 32 is suspended from and operated by cranks attached to shafts 35 and journaled above the tub 2 and rake aforesaid. There are four cranks 33, two forward and two to the rear, which have connecting-rods 34 attached to and supporting the said rake-frame. The shafts 35 are journaled on a frame 35^a, erected over the tub 40 for that purpose. The shafts 35 are driven by means of a sprocket-chain 36 from a sprocket 37 on the power-shaft 5 to a sprocket 38 on the forward shaft 35. The rear shaft 35 is operated simultaneously with the forward shaft 45 50 by a sprocket-chain 39, connecting two similar sprockets 40 on the said shafts 35. The swing-frame 7 8 with its fork 10 is oscillated by means of pitman-rods 41, which have one end pivotally attached at a suitable point on the arms 7 and the other ends pivoted to the forward cranks 33.

The rake-frame 31 32 is oscillated to and fro by pitman-rods 42, attached thereto and to the shaft 9. The rake-frame has rake-shafts 43 arranged with their length crosswise on said frame, which are journaled in suitable bearings and provided with tines or teeth 44 depending therefrom. Said shafts 43 have upwardly-extending arms 45, which

are connected together by a rod or bar 46, as shown in Fig. 1. A pitman-rod 47 has one end attached to the top end of the forward arm 45 and its free end adjustably attached to one of the arms 7 for the purpose of oscillating the rakes 44.

Each part having been properly adjusted, power is applied to the pulley 6 and shaft 5. The relative sizes of the sprockets 13, 11, 37, and 38 are such that the shaft 35 will make one revolution as the wheel 13 is making two. The cranks 33 are adapted to oscillate the frame 7 8 through the medium of the pitman-rods 41, at the same time raising and lowering the rake. As the shaft 9 and fork 10 recede from the squeeze-rolls 1 and feed-rolls 30 3 the ratchet-pawl 26 engages the slot 25, thus revolving the shaft 9 and fork 10 through the medium of the ratchet-wheel 23. The above mechanism is revolved rearwardly so as to turn the fork over the shaft 9 as the same recedes, said fork 10 being about to descend into the tub as the shaft 9 reaches its rearward limit. As the fork 10 and shaft 9 begin their forward movement, said fork dips into the tub or vat, gathering its fibrous contents upon its members whereupon as it reaches a horizontal position the pawl 26 reaches a point in its revolution where its end engages with the pin 21, which is adjusted so as to be at a point in its revolution nearest 95 the shaft 9. As the said pin 21 engages the pawl 26 it is disengaged from the slot 25 and the rotation of the fork ceases and is held from dropping back by the pawl 29, which engages the slot 25. At the same time the forward movement of the fork and its load continues until carried over the rolls 3, when the pin 22 reaches a point in its revolution, having been adjusted so to do, where it engages the said pawl 29, releasing the same from the 100 notch or slot 25, allowing the fork 10 to drop on the said rolls 3, which draw the material from the fork. The fork then begins to recede again and is held in position by the pawl 29, which engages the notch 30, after the pin 105 22 disengages said pawl, until the pawl completes its second revolution and engages the slot 25. The pins 21 and 22 are adapted to be at their greatest distance away from the shaft 25 as their respective pawls are carrying the fork, so as to allow it to pass without tripping. As the frame 7 8 and shaft 9 recede from the rolls 3 and 1 the cranks 33 are rotating over the shafts 35 and at the same 110 time raising the rake 31 32. As the cranks 115 pass rearwardly the rake is also carried rearwardly by the pitman 42. The rake is dropped into the tub 2 by the cranks 33 and are drawn forward by the forward motion of the shaft 9. The rakes 44 are given an oscillating motion by the rods 46 and 47, which are controlled by the arm 7.

Many features shown in my drawings are

not new; but I have shown them only to illustrate the connection of my invention therewith. Such parts I do not claim, broadly; but

What I do claim as new, and desire to secure 5 by Letters Patent, is—

1. In a machine of the class described the combination with a suitable tub or vat of the swing-frame, suspended from the power-shaft journaled in suitable posts and carrying the 10 fork-shaft, the fork rigidly attached to the shaft, the shaft 35 carrying the cranks 33 and communicating with the power-shaft, the pitman-rods 41 attached to the arms 7 and cranks 33 and means for rotating the fork-shaft intermittently, all substantially as shown and described. 15

2. In a machine of the class described the combination with the tub or vat of the power-shaft journaled on the posts 4, the swing-frame 7 20 8 suspended from the power-shaft, and adapted to carry the fork-shaft, the fork rigidly attached thereto, the pitman-rods 41 connected to the arms 7 and cranks 33 and operated by the cranks 33 on the shaft 35 25 which is journaled on a frame 35^a, the said shaft 35 operated from the power-shaft, the sprocket 13 loosely mounted on the fork-shaft, and operated from the power-shaft, the ratchet-wheel 23, having the slot or notch 25 30 in its periphery, rigidly mounted on the fork-shaft, the pawl 26 pivoted on the sprocket 13, the pawl 29 mounted on the arm 7, the gear-wheel 14 rigidly attached to the shaft 9, the idler 16 journaled on the side of the arm 7 35 and adapted to engage the said wheel 14 and the gear-wheel 15, the said gear-wheel 15 rigidly attached to the shaft 17 and journaled in brackets 18 on the side of the arm 7, the shaft 17 having the cam 19 and the pins 21 22, 40 all substantially as shown and described.

3. In a machine of the class described the combination with the tub or vat 2 of the swing-frame mounted and suspended from a power-shaft journaled on posts above the tub or vat, 45 the fork-shaft 9 journaled in the lower ends

of the swing-frame, the fork 10 rigidly attached to said shaft, means for rotating said fork-shaft intermittently, in concert with the oscillation of the swing-frame, the shafts 35 50 journaled above the tub or vat, the cranks 33 secured thereon, the links 34 pivoted to said cranks and to a suitable rake-frame, having rakes secured therein, the pitman-rods 41 secured to the swing-frame and two of the cranks 33, the pitman-rods 42 journaled on the shaft 55 9 and to the rake-frame and means for rotating the said shafts 35 in concert with the oscillation of the swing-frame and the rotation of the fork-shaft 9, all substantially as shown and described. 60

4. In a machine of the class described the combination with a tub or vat, of the swing-frame suspended from a power-shaft journaled on posts above the tub or vat, the fork-shaft 9, journaled in the lower ends of the swing-frame, the fork 10 rigidly attached to said shaft, means for rotating said fork-shaft intermittently in concert with the oscillation of the swing-frame, the shafts 35 journaled above the tub or vat, the cranks 33 secured thereon, 70 the links 34 pivoted to said cranks, and to a suitable rake-frame, said rake-frame having rakes secured therein, the pitman-rods 41 secured to the swing-frame and two of the cranks 33, the pitman-rods 42 journaled on the shaft 75 9, and to the rake-frame, means for rotating the said shafts 35 in concert with the oscillation of the swing-frame and the rotation of the fork-shaft 9, the rakes 44 having the arms 45, the connecting-rod 46, secured to said 80 arms 45, and the rod 47 secured to one of the arms 45 and to the arm 7 of the swing-frame, all substantially as shown and described.

In testimony whereof I have signed my name to this specification in the presence of two subscribing witnesses. 85
